SAXOPHONE

Leon Leblanc, Paris, France, assignor to G. Leblanc Corporation, Kenosha, Wis., a corporation of Wisconsin

Filed June 14, 1961, Ser. No. 117,071

10 Claims. (Cl. 84—385)

This invention relates to the art of musical instruments, particularly wind instruments, and most specifically a saxophone.

The principal objects of this invention are to produce a musical wind instrument of the open tube type, such as a saxophone, which is more reliable, is easier to regulate, and is simpler to manufacture.

It is a further object of this invention to provide such an instrument wherein the keys and pads controlled by the left hand are pivotable about three axes, while those controlled by the right hand are pivotable about two axes.

Yet another object of this invention is to provide a musical wind instrument such as a saxophone wherein the contacting parts of the interconnections between keys have larger bearing surfaces, and wherein the parts have better leverage.

Specifically, it is an object of this invention to provide a musical wind instrument such as a saxophone in which the driving or pressure points acting to close the various pads are disposed close to the holes to be closed.

It is further an object of this invention to provide a musical wind instrument such as a saxophone wherein the small pads to be operated by the left hand are pivotally mounted about a common axis, wherein each pad or key is independent, but wherein all thereof are interconnected.

It is yet another object of this invention to provide a musical wind instrument such as a saxophone wherein all of the small keys or pads are independent but operatively interconnected.

It is a further object of this invention to provide an improved high F key.

Other and further objects and advantages of the present invention will be apparent from the following description when taken in connection with the accompanying drawings wherein:

FIG. 1 is a front perspective view of an alto saxophone constructed in accordance with the principles of this invention;

FIG. 2 is an enlarged elevational view of a portion of the saxophone, embodying the keys to be played by the right hand;

FIG. 3 is an enlarged left side view of the saxophone showing the bell and adjacent parts;

FIG. 4 is a partial back view of the saxophone as taken along the line 4—4 in FIG. 3; FIG. 3 being taken along the line 3—3 in FIG. 4;

FIG. 5 is a horizontal cross-sectional view as taken along the line 5—5 in FIG. 3;

FIG. 6 is a slightly skewed, substantially left hand view of the upper portion of the saxophone as taken along the line 6—6 in FIG. 7;

FIG. 7 is an elevational view taken from slightly to one side of the front of the saxophone and showing the upper portion thereof as taken along the line 7—7 in FIG. 6; and

FIG. 8 is a horizontal cross-sectional view as taken along the line 8—8 in FIG. 7.

Referring first to FIG. 1, there is shown an alto saxophone generally designated by the numeral 10, and comprising a body 12, tapering in diameter from top to bottom, and having an upturned and outwardly flaring bell 14 at the lower end thereof. The body is provided at the upper end with the usual neck-pipe receiver 16 and neck-pipe receiver screw 18. An angulated neck-pipe 20 fits

2

in the receiver, and is clamped in place by the screw. The neck-piece has a brace 22 thereon, and at the upper end is provided with a generally cylindrical cork covering or overlay 24 on which the mouthpiece 26 fits.

5 Most of the keys, although by no means all thereof, are shown in FIG. 1, although the figure is on a sufficiently small scale that most of the connections and mechanisms are not shown in detail. Thus, there is in the neck an octave hole 28 closed by an octave key 30 having an upper portion 32 thereof overlying the neck-pipe and pivotally mounted at 34. The bottom or tail end of the octave key is split and encircles the lower portion of the neck-pipe and receiver and has a bight 36, engaged by a mechanism controlled in part by a thumb spatula (not shown).

10 The keys and holes which are shown in FIG. 1 include the high F tone hole and key 38, and the adjacent high E key 40. The D[#] spatula may be seen at 42, along with the high D spatula 44, and the high F spatula 46. 15 The G key 48 is immediately below or downstream from the F spatula 46.

20 Returning up to a position adjacent the D[#] spatula 42, there is a C[#] key 48. The finger-piece 50 of the high F key overlies the B key 52. The B_b "bis" key 54 is positioned adjacent the B key 52. The A key 56 overlies this key, and operates through suitable connections hereinafter to be described to operate the A key cup 58. Immediately adjacent the A key cup 58, there is the G resonator key cup 60. All of these keys and key cups are 25 operated by the left hand, as will be understood by those skilled in the art, as is the G key cover 62.

30 Turning now to the keys and key cups operated by the right hand, immediately below the G cup 62 is the F resonator key cup 64, followed by the F key cup 66, the F[#] key cup 68, the D key cup 70, and the relatively small Eb key cup 72.

35 As will be observed, the F resonator cup 64, the F[#] cup 68, and the Eb cup 72 are of relatively small size, as compared with the intervening cups 66 and 70. Substantially at the bight or crook leading up to the bell 14 there is found on one side a C key cup 74 having a key guard 76 thereover. This key cup 74 covers the C tone hole that is known as the low C tone hole. On the opposite side of the bell and spaced slightly above the C cup 74, there is a low C[#] key cup 78. Above this is the low B key cup 80, and above this is the low B_b cup 82. A guard 84 covers the key cup 78, while a guard 86 covers the cups 80 and 82.

40 Continued attention should be paid to FIG. 1, and further attention should be directed to FIG. 2 for certain of the constructional details of the keys and key cups operated by the right hand. Thus, there are three aligned posts 88, 90, and 92, each of the double variety. A hinge rod 94 is pivoted between the inner pivot of post 88 and a short post 93. A hinge rod 95 is aligned with hinge rod 94 and is pivoted between post 93 and the inner pivot of post 90. As will be understood, hinge rod 94 is actually a tube, as are other hinge rods hereinafter set forth. However, the conventional nomenclature of "hinge rod" is used throughout. Similarly, the hinge rod 96 is aligned with hinge rods 94 and 95 and is pivoted between the inner pivots of the post 92. The hinge rod 98 is pivoted between the outer pivots of the posts 88 and 90, while the hinge rod 100 is aligned with the hinge rod 98 and is pivoted between the outer pivots of the post 90 and 92.

45 At the upper end of the hinge rod 94 there is provided an arm 102 extending laterally to the left, as viewed in FIG. 2. At the outer end, this arm has a set screw 104 with a lock nut 106 thereon. The set screw is slotted at the upper end, and has a flat head (not shown) at the lower end having a felt covering on the surface thereof.

toward the body of the instrument. The remaining adjustment set screws hereinafter to be mentioned are similarly constructed. The felt at the lower end of the set screw 104 bears on an enlargement at the end of a lever 108 fixed on a hinge rod 110 pivoted at its lower end on a post 112. The hinge rod 110 will be discussed herein-after in greater detail in connection with another figure.

An arm 114 extends to the left from the hinge rod 94 and carries the F resonator key cup 64. As will be observed in FIG. 1, this cup normally is raised above the F resonator hole 116. It is spring-urged to this position by a needle spring 117 extending from the post 88 and engaging a spur (not shown) beneath the hinge rod 94.

An arm 118 extends to the left from the hinge rod 95 on which it is fixed, and at the outer end thereof carries a set screw and lock nut adjustment device 120 similar to the set screw 104 and lock nut 106 previously described. The felt pad on the other side of the set screw bears against the top of the key cup 64. At the lower end of the hinge rod 95 there is a laterally extending arm 122 on which the key cup 68 is secured. A needle spring 124 extends up from the post 90 and bears against a spur 126 on the hinge rod 95 for normally maintaining the arms 118 and 122 in raised position, whereby the cup 68 normally is spaced above the F# hole 128.

A lever 130 is fixed on the upper end of the hinge rod 96 and extends out over the key cup 68, carrying a mother-of-pearl fingerpiece 132 at the outer end. A lateral fixture on the arm 130 carries a set screw and lock nut adjustment 134 similar to those previously described, the felt on the under face of the set screw bearing against the top of the key cup 68 for closing of the F# key cup on the F# hole 128 when it is so desired. A spur 136 immediately adjacent the arm 30 is engageable with a stop 138 to limit raising of the lever 130 under the influence of a needle spring 140 fixed to the post 92 and bearing against a spur 142 on the under side of the hinge rod 96. Such stop acts through the overlying levers 130 and 118 and the corresponding key cups 68 and 64 to limit raising of these parts under the force of their respective springs.

Near the lower end of the hinge rod 96 there is an arm or point 144 which is fixed to the hinge rod, and which carries the Eb key cup 72 in raised position relative to the underlying Eb hole 146.

A laterally extending arm 148 is fixed on the hinge rod 98 relatively toward the upper end thereof, and is provided at its outer end with a set screw and lock nut adjustment 150, the felted underside of which adjustably bears against the key cup 64. Slightly below the center of the hinge rod 98 is an arm or point 152 on which is fixed the key cover 66. A needle spring 156 fixed in the post 90 bears against a spur 158 on the underside of the hinge rod 98 normally to hold key cover 66 and the arm 148 in raised position. A stop arm 160 on the hinge rod 98 is engageable with the body 12 of the saxophone to limit such outward movement.

A laterally extending arm 162 is fixed on the hinge rod 100 relatively toward the upper end thereof, and at its outer end is provided with a set screw and lock nut adjustment 164 of the type previously described, the felted undersurface thereof bearing against the key cup 68. The hinge rod 100 further has fixed thereon an arm or point 166 secured to and carrying the key cup 70. This key cup is provided with a mother-of-pearl finger piece 168, and a generally similar finger piece 170 is provided on the F key cup 66. A needle spring 172 fixed in the post 92 bears against a spur 174 on the underside of the hinge rod 100 normally to hold the key cup 70 and the arm 162 in raised position. The hinge rod 100 is provided with a stop arm 176 engageable with the body 12 of the saxophone to limit such outward movement.

With reference again to FIG. 1 the low C key cup 74 will be seen to be fixed on an angulated arm or point 178 fixed to the hinge rod 180 pivoted between the inner

5 pivots of a pair of spaced posts 182 and 184. A low C spatula key 186 is also fixed on the hinge rod 180. The upper edge of the spatula key 186 is provided with a roller 188 rotatable about an axis substantially perpendicular to the hinge rod 180. An outer hinge rod 190 is pivoted between the outer pivots of the posts 182 and 184, and has fixed thereto a spatula key 192, specifically the Eb spatula. This spatula is provided with a roller 194 along its lower edge. The rollers 188 and 194 greatly facilitate the placement of the finger on one or the other of the spatulas 186 and 192 without interference with the other. An arm (not shown) fixed to the hinge rod 190 is also fixed to the low Eb key cup 196 (FIGS. 3 and 4) covering the low Eb tone hole 198.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

5 pivots of a pair of spaced posts 182 and 184. A low C spatula key 186 is also fixed on the hinge rod 180. The upper edge of the spatula key 186 is provided with a roller 188 rotatable about an axis substantially perpendicular to the hinge rod 180. An outer hinge rod 190 is pivoted between the outer pivots of the posts 182 and 184, and has fixed thereto a spatula key 192, specifically the Eb spatula. This spatula is provided with a roller 194 along its lower edge. The rollers 188 and 194 greatly facilitate the placement of the finger on one or the other of the spatulas 186 and 192 without interference with the other. An arm (not shown) fixed to the hinge rod 190 is also fixed to the low Eb key cup 196 (FIGS. 3 and 4) covering the low Eb tone hole 198.

Also in FIG. 1, details thereof being omitted due to the scale of the figure, there is a chromatic F# key 200 having a mother-of-pearl finger piece thereon, and fixed to a longitudinal hinge rod 202. An arm on the hinge rod 202 (said arm being omitted from the drawings) carries the chromatic F# key cup 204 (FIGS. 3 and 4) covering the chromatic F# hole 206. Conventional needle springs (not shown) are provided for normally holding closed the chromatic F# key cup 204, for holding closed the low Eb key cup 196, and for normally holding open the low C key cup 74.

Preferably guards are provided for the Eb tone hole 198 and key cup 196, and for the chromatic F# key cup 204 and tone hole 206, although these have been omitted for clarity in the drawings. There is also preferably provided a thumb rest 208 on the body immediately below the chromatic F# tone hole 206. Additionally, a neck strap eyelet 210 preferably is provided on the back side of the saxophone, as is conventional.

Referring now to FIGS. 3-5, wherein the hinge rods 98 and 94, 95 and 96 have been shown only in part, and most of the connections thereto have been omitted, there will be seen three additional main axes. In particular, there is provided a relatively short, generally longitudinal hinge rod 212 pivoted between posts 214 and 216. The hinge rod 212 carries the angulated arm or point 218 on which the C# key cover 78 is mounted. A spur 220, seen in the background of FIG. 4, is engaged by a needle spring 222 which biases the key cup 78 lightly toward open position.

A hinge rod 224 is aligned with the hinge rod 212, and is pivoted between the post 216 and a post 226. This hinge rod is relatively long, and toward its lower end carries a laterally extending arm 228 having at its outer end a set screw and lock nut adjustment 230 of the type previously described. The felted undersurface of the set screw is engageable with the key cup 80, which normally is open, and is operable to close this key cup on the underlying tone hole.

Spaced up a bit from the arm 228, the hinge rod 224 carries a laterally extending arm or point 232 on which the Bb key cup 82 is mounted. At its upper end, the hinge rod 224 has fixed thereto an L-shaped lever 234 carrying a spatula key 236 having a roller 238 along its longitudinal edge (the right edge as viewed in FIG. 3), and a transverse roller along its upper transverse edge 240. A needle spring 242 underlies the hinge rod 224, bearing against a spur (not shown), whereby to pivot the hinge rod so that the spatula key 236, the key cup 82, and the arm 228 are normally in raised position. A stop arm 244 is fixed on the hinge rod 224 immediately adjacent point 232, and is engageable with the body 12 of the saxophone 10 to limit the outward movement of the aforesaid parts.

A continuous, elongated hinge rod 246 is spaced to the right (as viewed in FIG. 3) of the hinge rods 212 and 216, and is pivoted between a pair of posts 248 and 250. Near the lower end thereof, the hinge rod 246 has an angulated arm 252 extending out over the top of the C# key cover 78, bearing at the outer end a set screw and lock nut adjustment 254 of the type previously de-

scribed. The key cup 78 normally is in closed position, and the arm 252 is normally raised. However, the hinge rod 246 upon pivoting thereof lowers the arm so that the felt undersurface of the set screw is engageable with the top of the cup 78 to hold it in closed position.

Shortly above the arm 252, the hinge rod 246 has a lateral arm or point 256 fixed thereon. The low B key cover or cup 80 is fixed on this point, and normally is in raised or open position under the influence of a spring 258 at the upper end thereof, said spring being the usual needle spring fixed to the post 250 and bearing against a spur (not shown) under the hinge rod 246.

At the upper end of the hinge rod 246 there is fixed a laterally extending arm 260 carrying a spatula 262 immediately above the spatula 236. This spatula has a roller 264 of the type previously described along its right edge, as viewed in FIG. 3.

A slightly longer hinge rod 266 is disposed generally parallel to and to the right of the hinge rod 246, as viewed in FIG. 3. This hinge rod is pivotally mounted between a pair of posts 268 and 270. The hinge rod 266 near its lower end is provided with a lever or arm 272 extending to the left, and a lever 274 fixed on the lower end of the hinge rod 212 overlies and is engageable with this lever. A needle spring 276 is fixed in the post 268 and is engageable with a spur 278 beneath the hinge rods 266 to bias the hinge rod 266 normally to hold the lever or arm 272 up against the underside of the lever or arm 274. A guard preferably overlies a substantial portion of the hinge rod 266 near the lower end thereof, but has been omitted for simplicity of illustration.

At the upper end of the hinge rod 266 there is fixed a lateral arm 280 (FIGS. 3 and 5, particularly) on which is mounted a spatula 282. This spatula is as long as the spatulas 236 and 262 taken together, in the longitudinal direction of the saxophone. Two rollers, 284 and 286, respectively, are positioned on this spatula, respectively adjacent the rollers 238 and 264.

The post 270 is a double post and the hinge rod 266, previously mentioned, is pivoted in the outer pivot thereof. The inner pivot of the post 270 is aligned with the pivot of a post 288, and three hinge rods 290, 292 and 294 are pivoted between these posts and are pivotable independently of one another except for certain interconnections hereinafter to be set forth. The hinge rod 290 has a laterally extending arm 296 thereon, which overlies the outer end of an arm 298 extending to the right from the upper end of the hinge rod 94. No spring bias is applied to the hinge rod 290.

As seen in FIG. 4, the hinge rod further has a short lever arm or spur 300 projecting toward the body 12. This spur has at the lower end thereof a simple set screw adjustment 302 which bears against one arm of a swivel 304 pivotally mounted at 306 on the body 12.

The opposite end of the swivel 304 is engageable with a non-adjustable spur or short lever arm 308 near the lower end of the hinge rod 292. An arm or point 310 extends to the left from the hinge rod 292 immediately above the spur 308 and carries the G# key cup 312. A needle spring 314 is fixed in the post 288 and bears against a spur 316 extending from the hinge rod 292 toward the body 12. The spring tends to open the G# key cover 312, but this tendency is normally overcome, as will be set forth shortly hereinafter.

A short lever arm or spur 318 extends toward the body 12 from the hinge rod 292 and engages one end of a swivel 320 pivotally mounted on the body at 322. The opposite end of the swivel engages a short lever arm or spur 324 fixed on and extending toward the body from the lower end of the hinge rod 294. Near the upper end of the hinge rod 294 is a laterally extending arm 326 carrying the G# spatula 328. A needle spring 330 extending from the post 270 engages a spur 332 on the underside of the hinge rod 294, whereby normally to hold the spatula 328 in raised position. The spatula

328 is substantially on a level with and laterally coextensive with the spatulas 262 and 282. As is shown in FIG. 5, there are two studs 334 and 336 fixed to the underside of the spatula 328, and respectively underlying the upper edges of the spatulas 282 and 262, whereby depression of either of these latter two spatulas will result in depression of the spatula 328. The spatula 328 is capable of being depressed independently.

Operation and interconnection of the just described 10 spatulas is such that if the spatula 328 alone is depressed, the G# key cup 312 rises to open the G# hole thereunder. When any of the remaining three spatula keys 262, 236, or 282 is depressed, the G# key cup again rises to open the G# hole. If it is the spatula 282 that is depressed, the C# key cup 78 rises to open the C# hole therebeneath. If the spatula 262 is depressed, the low B key cup 80 lowers to close the low B hole, and the arm 252 lowers to hold closed the low C# hole 78. If the spatula 236 is depressed, then both the low B key cup 80 and the low Bb key cup 82 lower to close their respective holes, and the arm 252 also lowers to hold closed the C# hole.

Referring now to FIGS. 6-8, and at first specifically FIG. 7, there will be seen the hinge rod 110 previously mentioned pivoted at the lower end on the post 112. At the upper end, the hinge rod 110 is pivoted on the inner pivot of a post 338. In addition to the lever 108 previously mentioned, the hinge rod 110 bears a transverse arm or point 340 on which is mounted the G resonator key cup 60. A needle spring 342 fixed in the post 112 bears against a spur 344 beneath the hinge rod 110, and biases the hinge rod so as normally to hold the G resonator key cup 60 in raised position. As will be seen in FIG. 6, the key cup has a pad 346 secured therein, for closing the G resonator hole 348. Similarly, all of 20 the other key cups previously and hereinafter described are provided with pads, although specific reference thereto is omitted for simplicity.

A hinge rod 350 is aligned with the hinge rod 110 and is pivoted between the inner pivot of the post 338 and the inner pivot of a post 352. This hinge rod has a laterally extending arm 354 underlying the end of a longitudinal extension 356 on the G resonator key cup 60, having at the upper or outer end thereof a set screw and lock nut adjustment 358 of the type heretofore described. The arm 354 normally is maintained in raised position against the underside of the set screw and the extension 356 by means of a needle spring 360 fixed in the post 338 and bearing against a spur 362 on the underside of the hinge rod 350.

At the upper end of the hinge rod 350 there is provided an arm or point 364 carrying the Bb bis key 54. There is a generally longitudinal extension 366 on this key cup, bearing at the outer end thereof a set screw and lock nut adjustment 368 of the type heretofore described.

A hinge rod 370 is pivoted between the inner pivot on the post 352 and the inner pivot of another post 372, the hinge rod 370 being aligned with the hinge rods 350 and 110. An arm 374 is fixed to and extends laterally from the hinge rod 370 and is held up beneath the set screw and lock nut adjustment 368 by a needle spring 376 fixed in the post 372 and bearing against a spur 378 beneath the hinge rod 370. Finally, a laterally extending arm or point 380 is fixed on the hinge rod 370 near the upper end thereof and carries the C# key cover 48.

Between the outer pivots of the posts 338 and 352 there is pivoted a hinge rod 382 having a laterally extending arm or point 384 thereon carrying the A key cup 58. A needle spring 386 fixed in the post 338 bears against a spur 388 on the underside of the hinge rod 382, normally to maintain the A key cup 58 raised. A stop arm 390 on the hinge rod 382 curves over and around the hinge rod 380 and down toward the body 12 of the saxophone 10 where it is engageable with a protuberance 392 on the surface of the body to limit movement of the stop arm 390 to the right, as viewed in FIG. 7, thereby limit-

ing the uppermost position of the A key cover 58. The hinge rod 382 also has the A key 56 secured thereon by means of a laterally extending arm 394. A set screw and lock nut adjustment 396 is fixed on the side of the arm 394 for bearing against the Bb bis cover 54.

A hinge rod 398 is aligned with the hinge rod 382, being pivoted between the outer pivots of the post 352 and the post 372. This hinge rod has fixed to it the laterally extending arm 400 carrying the B key cover 52 with a mother-of-pearl finger-piece 402 thereon. The cover 52 is normally spring biased to raised position by a needle spring 404 fixed in the post 372 and bearing against a spur 406 on the underside of the hinge rod 398. Adjacent the upper end thereof, the hinge rod 398 is provided with a laterally extending arm 408 having a set screw and lock nut adjustment 410 at the outer end thereof bearing against the normally raised C# key cover 48. A long hinge rod 412 is pivoted between a post 414 and the outer pivot of a double pivot post 416 near the top of the body 12. This hinge rod has at the bottom end thereof a laterally extending arm 418 bearing a spatula 420. This arm is engageable with a post 422 to limit movement of the arm 418 and pivoting the hinge rod 412. (The post 422 is in the background in FIG. 7.)

At the upper end of the hinge rod 412, there is a laterally extending arm or point 424 which carries the E key cup or cover 40.

Directly beneath the hinge rod 412 there is a hinge rod 426 pivoted between the posts 428 and 430. Near the bottom or lower end of this hinge rod an arm 432 fixed thereon projects up between the hinge rods 412 and 110, and over the hinge rod 110 to the top of the key cup or cover 62 to which it is fixed. A needle spring fixed in the post 428 and identified as 434 bears against a spur 436 on the hinge rod 426, and normally maintains the G cup or cover 62 in raised position.

Somewhat over the arm 432, another arm 438 extends up between the hinge rods 412 and 110 from the hinge rod 426, and extends above the hinge rod 110 to a position overlying the G resonator key cup 60. The arm 438 has a set screw and lock nut adjustment 440 at the outer end thereof engageable with the cup 60.

Farther up the hinge rod 426 there is an arm 442 extending laterally beneath the hinge rod 350 and carrying the G key 48. At the extreme upper end of the hinge rod 426 there is a short arm 444 extending in toward the body 12 of the saxophone 10 and engageable with the hooked end 446 of a swivel 448 pivotally mounted on the body at 450. The hooked end 446 of the swivel 448 extends around the post 430.

A hinge rod 452 is pivoted between the post 430 and the inner pivot of the double pivot post 416. This hinge rod carries a short arm 454 extending in toward the body 12 and engageable with the opposite end of the swivel 448. The hinge rod 452 is not directly spring biased. It is controlled by the swivel, and also by a lateral arm (not shown) extending behind the body 12 of the saxophone for cooperation with the register mechanism (not shown).

A longitudinally extending spatula key 456 is spaced to the right of the group of key covers just discussed, and is pivoted about a transverse axis 458 between a pair of posts 460. The spatula key 456 at its upper end carries the F key cup or cover 38, and at its lower or tail end is provided with a spatula or finger piece 462. A leaf spring 464 normally holds the key cup 38 in hole closing position, and a heel 466 on the spatula key limits depression thereof under the influence of the artist's finger.

Immediately to the right of the spatula key 456 there is another longitudinally extending spatula key 468, the upper end thereof being offset somewhat to the right, whereas the upper end of the spatula key 456 is slightly offset to the left. The upper end of the spatula key 468 carries the D# key cover 470, while the lower end is provided with a finger piece or spatula 472. The spatula is mounted on a transverse hinge or pivot rod 474 pivoted

between a pair of posts 476. The spatula 468 is biased by a spring (not shown) similar to the spring 464 normally to hold the D# key cup in hole closing position.

Yet another spatula key 478 is mounted in longitudinal position to the right of the spatula 468, being pivotable about a transverse axis between a pair of posts 480, and bearing at the upper end the D key cup or cover 482. A finger piece or spatula 484 is provided at the lower end, and a leaf spring similar to those previously shown (not shown) normally holds the spatula with the key cup 482 in hole closing position.

A hinge rod 486 extends longitudinally in slightly skewed relation to the left of the spatula key 478, and to the right and over the spatula key 468, being pivoted between posts 488 and 490. The F# key cup 492 is carried by a lateral or transverse arm 494 at the upper end of the hinge rod 486, and a finger piece or spatula 496 is carried by a laterally extending arm 498 at the opposite end of the hinge rod 486. A needle spring 500 extends from the post 488 and bears against a spur 502 on the underside of the hinge rod 486 for biasing the key cup 492 into hole closing position.

Just to the left of the spatula 456, there is a short, generally longitudinal hinge rod 504 pivotally mounted between a pair of posts 506 and 508. Adjacent the upper end of this hinge rod, there is a laterally extending arm 510 positioned beneath the key 456, and adapted to lift this key. At the lower end there is a generally L-shaped lever 512 extending laterally in the opposite direction, and having a transverse extremity 514 thereon carrying a finger piece 516, preferably faced with mother-of-pearl. Thus, when the finger piece 516 is depressed, the C# key cup 48 is depressed, and the arm 510 raises the spatula 456 to raise the F key cup 38 from its tone hole.

All of the mechanical details of the saxophone have now been described, except for certain parts of the register mechanism, which mechanism forms no part of the present invention, and certain trill keys. Much of the operation has been described heretofore, and most of the rest of the operation will be obvious. One important feature, particularly to be borne in mind is that all of the smaller key cups are linked together. That is to say, if the finger piece 132 is depressed, all of the key cups 48, 54, 60, 64, 68 and 72 lower into closing position. It further will be observed that if any of the right hand finger pieces 170, 132, or 168 is depressed, the interconnection through the arms 298 and 296, and swivel 304 prevents the G# key cup 312 from opening. As will be appreciated, this is essential through proper playing of the lower notes below the position of the G# key cup. In particular, some of these lower notes are produced by the spatula keys 282, 262, and 236, depression of any one of which would open the G# hole in the absence of the interconnections just alluded to.

As will be appreciated, the keys to be operated by the left hand are mounted for pivoting about three different axes, allowing superior adjustment by way of the various set screw and lock nut adjustments referred to. Further, the bearing points, as by the undersurfaces of the set screws are remarkably close to the center lines of the holes to be closed. Similar advantages are gained by the provision of the two axes for the pivoting of the keys operated by the right hand. All of the small keys operated by the left hand operate about a common pivot, and similarly, all of the small keys operated by the right hand operate about a common pivot axis.

The large flat head of each set screw (see for example the one in FIG. 6 bearing on the C# key cup 48) with the felt thereunder provides a wide bearing surface, affording long life, and insuring against the parts getting out of adjustment by wear of contacting small parts.

The specific construction as shown herein is for illustrative purposes, and various changes in detail will no doubt occur to those skilled in the part. Such changes will be understood as forming a part of the present invention.

tion insofar as they fall within the spirit and scope of the appended claims.

The invention is claimed as follows:

1. In a musical wind instrument of the open tube type such as a saxophone having upstream and downstream ends, the combination comprising a hollow body having a plurality of tone holes therein substantially aligned axially of said body, alternate ones of said tone holes being of small diameter relative to the adjacent tone holes, a plurality of tone hole closure members, one for each of said tone holes, pivot mounting means mounting said tone hole closure members from said body for pivoting independently of one another, means normally maintaining all of said tone hole covers in raised hole open position, and means including one-way drive means interconnecting all of the closure members for said relatively small tone holes such that movement of any one of said small tone hole closure members to hole closing position effects urging of all of said small tone hole closure members upstream thereof to hole closing position, all small tone hole closure members downstream thereof remaining in raised hole open position.

2. In a musical wind instrument of the open tube type such as a saxophone having upstream and downstream ends, the combination comprising a hollow body having a plurality of tone holes therein substantially aligned axially of said body, certain of said tone holes being of small diameter relative to adjacent tone holes, a plurality of tone hole closure members, one for each of said tone holes, means pivotally mounting said tone hole closure members from said body including means mounting the closure members for the small tone holes for pivotal movement independent of one another, means normally maintaining the small tone hole covers in raised hole open position, and means operatively interconnecting all of the closure members for said relatively small tone holes such that movement of any one of said small tone hole closure members to hole closing position effects urging of all of said small tone hole closure members upstream thereof to hole closing position, all small tone hole closure members downstream thereof remaining in raised hole open position.

3. In a musical wind instrument of the open tube type such as a saxophone having upstream and downstream ends, the combination comprising a hollow body having a plurality of tone holes therein substantially aligned axially of said body, certain ones of said tone holes being of small diameter relative to adjacent tone holes, a plurality of tone hole closure members, one for each of said tone holes, means pivotally mounting said tone hole closure members from said body including means mounting the closure members for the small tone holes for individual pivoting, means normally maintaining the small tone hole covers in raised hole open position, and means rigid with each of the small tone hole closure members save the farthest upstream thereof respectively overlying in drivingly engageable position the next upstream small tone hole closure member whereby pivotal movement of any one of said small tone hole closure members to hole closing position effects urging of all of said small tone hole closure members upstream thereof to hole closing position, all small tone hole closure members downstream thereof remaining in raised hole open position.

4. The combination set forth in claim 3 and further including a part on each overlying member directly engageable with the hole closure member of the next upstream small tone hole.

5. The combination set forth in claim 4 wherein the engageable part comprises a set screw, and further including a lock nut thereon.

6. The combination set forth in claim 5 wherein each set screw has a large substantially flat head engageable with the underlying closure member.

7. In a musical wind instrument of the open tube type

75

such as a saxophone having upstream and downstream ends, the combination comprising a hollow body having a plurality of tone holes therein substantially aligned axially of said body, a plurality of tone hole closure members, one for each of said tone holes, means pivotally mounting at least some of said tone hole closure members from said body for pivoting independently of one another, means normally maintaining at least said some tone hole covers in raised hole open position, and means including one-way drive means interconnecting at least said some closure members such that movement of any one of said some tone hole closure members to hole closing position effects urging of at least all of said some tone hole closure members upstream thereof to hole closing position, all of said some tone hole closure members downstream thereof remaining in raised hole open position.

8. In a musical wind instrument of the open tube type such as a saxophone having upstream and downstream ends, the combination comprising a hollow body having a plurality of tone holes therein substantially aligned axially of said body, a plurality of tone hole closure members, one for each of said tone holes, means pivotally mounting at least some of said tone hole closure members from said body for pivoting independently of one another, means normally maintaining at least said some tone hole covers in raised hole open position, and means operatively interconnecting at least said some closure members such that movement of any one of said some tone hole closure members to hole closing position effects urging of at least all of said some tone hole closure members upstream thereof to hole closing position, all of said some tone hole closure members downstream thereof remaining in raised hole open position.

9. In a musical wind instrument of the open tube type such as a saxophone having upstream and downstream ends, the combination comprising a hollow body having a plurality of tone holes therein substantially aligned axially of said body, a plurality of tone hole closure members, one for each of said tone holes, means pivotally mounting at least some of said tone hole closure members from said body for pivoting independently of one another, means normally maintaining at least said some tone hole covers in raised hole open position, and means rigid with each of at least said some tone hole closure members save the farthest upstream thereof respectively overlying in drivingly engageable position the next upstream small tone hole closure member whereby pivotal movement of any one of at least said some tone hole closure members to hole closing position effects urging of at least all of said some tone hole closure members upstream thereof to hole closing position, all of said some tone hole closure members downstream thereof remaining in raised hole open position.

10. A musical wind instrument of the open tube type such as a saxophone comprising a hollow body having an upstream upper part and a downstream relatively lower part and having a plurality of tone holes therein substantially aligned longitudinally of the body and same in the upper body part and same in the lower body part, a like plurality of tone hole closure members, some of said tone hole closure members being on the upper part of the body and conventionally operable by the fingers of the left hand and others of said tone hole closure members downstream thereof being relatively on the lower part of the body and conventionally operable by the fingers of the right hand, three non-aligned hinge rod means supported from said body and extending substantially longitudinally thereof adjacent the upper body part tone holes, means respectively pivotally mounting the upper body part closure members about said three hinge rod means for pivotable movement to tone hole closing position, at least one such closure member being pivotable about each of said hinge rod means, two non-aligned hinge rod means supported from said body and extending longitudinally thereof adjacent the lower body part tone holes, and means

respectively pivotally mounting the lower body part closure members about said two hinge rod means for pivotal movement to tone hole closing position, at least one lower body part closure member being pivotable about each of said two hinge rod means, said body having an additional tone hole displaced from alignment with the previously mentioned tone holes, a closure member for said additional tone hole pivotally mounted from said body, said last mentioned closure member normally being in hole closing position, means including a key interconnected with said last mentioned closure member for removing it to raised hole open position, said body having a plurality of further tone holes, a like plurality of tone hole closure members therefor pivotally mounted from said body, means including a like plurality of keys interconnected with said plurality of further tone hole closure members for reversing the condition of opening and closing thereof, means interconnecting said plurality of keys with the additional tone hole key whereby operation of any of said keys effects movement of said additional tone hole closure member to raised hole open position, and means interconnecting the lower body part closure mem-
